(57) **CLAIM**

The ornamental design for a composite reinforced wood stud for buildings, as shown and described.

DESCRIPTION

FIG. 1 is a front perspective view showing my new design for a composite reinforced wood stud for buildings;

FIG. 2 is a right side elevational view;

FIG. 3 is a front elevational view;

FIG. 4 is a left side elevational view;

FIG. 5 is a rear elevational view;

FIG. 6 is a top plan view; and,

FIG. 7 is a bottom plan view.

The composite reinforced wood stud for buildings is shown with symbolic break in its length. The appearance of any portion of the article between the break lines forms no part of the claimed design.
